UNITED STATES PATENT OFFICE.

JOSEPH P. LEGGETT, OF CARTHAGE, MISSOURI.

FRAME FOR SUPPORTING AND CONFINING COILED SPRINGS.

No. 887,664.

Specification of Letters Patent.

Patented May 12, 1908.

Application filed July 5, 1907. Serial No. 382,251.

To all whom it may concern:

Be it known that J. P. LEGGETT, a citizen of the United States of America, residing in Carthage, in the county of Jasper and State of Missouri, have invented certain new and useful Improvements in Frames for Supporting and Confining Coiled Springs, of which the following is a full, clear, and exact description, reference being had to the accompanying drawings, forming part of this specification.

My invention relates to a frame for supporting single cone coil springs and in which is included means whereby the lower or base coils of the springs are rigidly held under tension upon base members of the frame, thus providing firm and secure fastenings for the springs to cause them to, at all times, act to take up all lost motion in the frame at the crossing points of the frame members at which the springs are located.

My present improvement is more particularly intended for use in the construction of bed bottoms for beds but the construction may be advantageously made use of in other articles wherein coiled springs are used and supporting frames therefor are necessary.

This application is filed in lieu of application Number 329,843, filed August 9, 1906 and allowed January 11, 1907.

Figure 1 is a perspective view of a portion of my spring supporting frame and part of a coil spring shown mounted thereon. Fig. II is a view partly in elevation and partly in cross section of members of the frame and the base coil of a spring seated on said members, the fastening members by which the base or supporting coil of the spring is secured being in the position assumed before they are applied to said coil for spring holding action. Fig. III is a similar view to Fig. II with the spring holding members spread into their holding position. Figs. IV to IX inclusive are views partly in elevation and partly in section illustrating modifications.

1 designates main frame bars which may be of any desirable number and which are arranged parallel with each other.

2 are reaches that connect the main frame bars, each of said reaches being provided at its ends with upturned clip arms 3 which are connected to the main frame bars by rivets 4 or other suitable means of fastening. The clip arms 3 extend above their points of connection with the main frame bars and terminate in out-turned lips 5. It will be un-

derstood that the reaches 2 are not present at the outer sides of the frame and to provide for the application of the coil springs on the outermost main frame bars 1 apply to said frame bars the clips 3' which are located opposite to the reach clip arms 3, also applied to said frame bars and terminating in lips 5', see Fig. I.

A designates a coiled spring having a base coil a that is adapted to rest upon the upper edge of a main bar 1 to which it is to be secured, the said base coil terminating in a hook a'. In mounting the springs upon the frame each spring is placed with its base coil resting upon the upper edge of a main frame bar 1 and surrounding the up-turned clip arms 3 of the reaches 2 while said arms are in the contracted position illustrated at the right hand side of Figs. I and in II. The base coils of the springs are so placed on said bars that the hook a' will serve to restrict the movement of said coil in one direction and the spring may readily be maintained in position to hold said spur against said bar until the base coil has been fastened in the manner now to be described.

After the base coils of the coil springs A are positioned on the main frame bars 1 while the clip arms 3 are in the contracted condition as seen in Fig. II, a suitable tool, for instance, such as that illustrated in dotted lines Figs. II and III, is applied to the clip arms and forced downwardly, whereby the clip arms are spread into the position illustrated in Figs. III and also at the left hand side of Fig. I. In spreading the clip arms they are caused to engage the base coils of the springs with the result that said base coils are forced downwardly while impinging on the main frame bars and placed under tension with the result of tightly clamping said base coils and so confining them that they will not be susceptible of movement and will moreover tend to hold the parts to which they are applied in a firm and unyielding condition without affecting the resiliency of the upper coils of the springs. When the clip arms are expanded as explained, the lips at the terminations of said arms project downwardly past the base coils of the springs and serve to prevent accidental displacement of the base coils from their positions beneath the clip arms.

In Fig. IV I have illustrated a modification in which a reach 2' extends beneath a main frame bar 1' and is connected thereto by a

rivet 4'. The reach in this construction is provided with inclined clip portions 3' that are adapted to be spread into the positions illustrated in full lines of said figure for the purpose of confining the base coil A of the spring that is applied to the reach, and whereby said coil is held under tension. Previous to the application of a suitable instrument to spread the reach clip portions, the reach occupies the elevated positions seen in dotted lines in order that the base coil spring may be passed thereunder.

In Fig. V I have shown another modification similar to that shown in Fig. IV with the exception that the reaches 2^a do not extend beneath the main frame bar 1^a but are individual members between the various main frame bars. The clip portions 3^a of the reaches 2^a are applied to the base in the same manner as the clip portions 3^c.

In Fig. VI I have illustrated another modification in which the reach 2^b is continuous and passes beneath the main frame bars 1^b without being attached thereto. The reaches in this instance have the clip portions 3^b that are applied to the base coils of the springs in the same manner as that described in connection with Fig. IV.

In Figs. VII and VIII I have illustrated another modification in which I provide for the base coils of the springs being mounted directly upon a reach 2^c and intermediate of the main frame bars by which the reaches are supported. In this construction the reach has formed therein at intervals, inverted V-shaped clip members 3^c provided with lips 5^c which overhang portions of the reach beneath them. These lips are sufficiently elevated above the main portions of the reach to provide for the lips being projected over the base coil of a spring resting on said reach and when the clip portion is depressed or flattened out into a spread condition as seen in Fig. VIII, the clip portions 3^c serve to confine the base coils of the springs and the lips 5^c project beyond said base coil to prevent displacement of the coil from the reach on which it is confined.

In Fig. IX I have illustrated another modification in which I use single clip sections 2^d in lieu of reaches leading from the main bars of the frame. These single clip sections 2^d are applied to the main frame bars and are provided with clip arms 3^d terminating in lips 5^d. The clip sections may be secured to the main frame bars by rivets 4^d or they may be loosely applied to said frame bars as may be desired. The application of the base coils of the springs to the clip sections 2^d is similar to that described relative to the construction illustrated in Figs. I to III inclusive.

Having thus described my invention, what I claim and desire to secure by Letters Patent, is:

65 1. In a coiled spring securing means, a

spring supporting member and a spreadable spring engaging clip, comprising a pair of arms extending upwardly and outwardly from said supporting member, substantially as set forth.

2. A coiled spring supporting and securing means comprising a spring supporting bar and spreadable spring engaging bars and spreadable spring engaging members fitted to said bar and provided with lips, substantially as set forth.

3. A coiled spring supporting and securing means comprising a spring supporting bar, and spring engaging members fitted to said bar and extending outwardly therefrom, said spring engaging members terminating in lips, substantially as set forth.

4. A coiled spring supporting and securing means comprising a series of spring supporting bars, and reaches fitted to said bars, said reaches being provided with spring engaging members extending outwardly and upwardly from the sides of said bars, substantially as set forth.

5. A coiled spring supporting and securing means comprising a series of spring supporting bars, and reaches fitted to said bars, said reaches being provided with spring engaging members extending outwardly from said bars and terminating in lips, substantially as set forth.

6. In a coiled spring securing means, a spring supporting member, spring engaging arms extending transversely from opposite sides of said supporting member and provided with downwardly bent lips, and a coil spring, the lower whirl of which is supported by said supporting member, said lower whirl being engaged by said lips and held bent downward and under tension by said arms.

7. In a coiled spring securing means, a spring supporting member, spring engaging arms extending transversely from opposite sides of said supporting member and having lips, and a coil spring having its lower whirl supported by said supporting member and engaged by said lips, said arms and with them the lower whirl of the spring being bent downward thus holding the lower whirl of the spring bent and under tension.

8. In a coiled spring securing means, a flat bar disposed edge up, spring engaging members extending transversely from opposite sides of said bar and having downwardly extending lips, and a coil spring having its lower whirl resting on the upper edge of said bar and engaged by said lips and held bent downward and under tension by said members.

9. In a coiled spring securing means, a spring supporting bar, and spreadable spring engaging members engaging said bar and provided with lips, and a coil spring having its lower whirl resting upon said bar, the spring engaging members being spread so as

to have the lips engage and bend and hold under tension the lower whirl of the spring.

10. In a coiled spring securing means, a spring supporting bar, spring engaging members terminating in lips and fitted to and extending outwardly from the said bar, and a coil spring supported by said bar and having its lower whirl engaged by said lips and held bent and under tension by said members.

11. In a coiled spring securing means, a series of spring supporting bars, reaches connecting said bars and provided with spring engaging members terminating in lips, and coil springs supported on said bars and having their lower whirls engaged by said lips, the lower whirls of the springs being held bent and under tension by said spring engaging members.

12. In a coiled spring securing means, a

series of spring supporting bars, reaches connecting said bars and provided with spring engaging members extending transversely from the bars and terminating in lips, and coil springs having their lower whirls supported on said bars, the spring engaging members being bent downward and with them the lower whirls of the springs, whereby the lips are caused to engage the lower whirls of the springs and the lower whirls are held bent and under tension.

In testimony whereof I have signed my name to this specification in presence of two subscribing witnesses.

JOSEPH P. LEGGETT.
